CLAIM

The ornamental design for the decorative lights, as shown and described.

DESCRIPTION

FIG. 1 is a front perspective view of the decorative lights, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 2.

The broken lines in the drawings illustrate the portions of the decorative lights, which form no part of the claimed design. The dash-dot-dash broken lines encircling the enlarged views are for annotative purposes only and form no part of the claim thereof.

The light string is shown with multiple symbolic breaks along its length. The dash-dot-dot-dash broken lines shown in the drawings are for illustrating the symbolic break only. The appearance of any portion of the article between the break lines forms no part of the claimed design.
